UNITED STATES PATENT OFFICE.

CHARLES LEWIS LEHMAN AND JOHN GEORGE CONNELL, OF CORONADO, ALBERTA, CANADA; SAID CONNELL ASSIGNOR OF ONE-HALF OF THE ENTIRE RIGHT TO HENRY CONRAD VAKINER, OF EDMONTON, ALBERTA, CANADA.

AUTOMOBILE RADIATOR.

Application filed March 14, 1922. Serial No. 543,798.

To all whom it may concern:

Be it known that we, CHARLES LEWIS LEHMAN and JOHN GEORGE CONNELL, citizens of the Dominion of Canada, of the 5 town of Coronado, in the Province of Alberta, Canada, have invented new and useful Improvements in Automobile Radiators for the Cooling of Water, and which the following is a specification.

10 The invention relates to radiators for internal combustion engines and the principal object thereof is to produce a radiator of which the parts may be easily removed by an unskilled workman for the purposes of 15 repair and renewal.

With this object in view the invention consists in the construction and combination of parts of which a preferred embodiment is illustrated in the accompanying 20 drawings, in which:

Figure 1 is a perspective view of the invention, a portion of the fins being shown cut away.

Figure 2 is a similar view of the radiator 25 and fins but with the latter removed.

Figures 3 and 4 are detail perspective views of the top and bottom tanks respectively of the radiator.

Figures 5, 6, 7 and 8 are detail perspective views of a tube, a top strip, a bottom strip and a tube section respectively.

Essentially the invention comprises the lower and upper tanks A and B of which the former is provided with a centrally disposed water inlet D and the latter with a similarly shaped outlet D'. In the top face of the lower tank and bottom face of the upper tank there are formed the rectangular openings G' for the reception respectively of the perforate plates or strips G² and G³, the latter carrying the nipples G⁴ in registration with the perforations. The nipples G⁴ are interiorly threaded for the reception of the extremities of the circulating tubes or pipes G⁵ which at their remote ends are provided with the running threads G⁶ for the reception of nuts B², the lower ends of the tubes threadingly engaging the perforations in the plates or strips G² and

a water tight connection being effected by 50 securing the nuts B² thereafter into firm engagement with the upper faces of the plates or strips G². The plates or strips G² and G³ are secured in place in openings G' by brazing or soldering. 55

In order that the tubes may be adequately protected, a series of parallel fins C² is provided, slotted as indicated at C³, so that they may be arranged transversely of the pipes or tubes G⁵ with their front edges in 60 the plane of the front faces of the upper and lower tanks, the slots providing clearance spaces for the tubes. The fins at their ends are secured, as by soldering or brazing, with the upright plates or strips C which, 65 when the fins are disposed in proper position, shield the two outer series of pipes or tubes G⁵. The fin section is secured in place by Z bolts D soldered or otherwise secured to the top and bottom faces respectively of 70 the uppermost and lowermost fin and their threaded extremities pass through the ears E formed on the upper and lower tanks, the threaded extremities of the Z bolts receiving nuts for securing the fin structure as 75 a whole in place.

When it is desired to replace any one of the tubes, the fin structure is removed by detaching the nuts secured to the Z bolts D, when the fin structure may be withdrawn 80 from the radiator and the defective tube removed after loosening its lock nut B².

The invention having been described, what is claimed as new and useful is:

1. In a radiator, an upper tank, a lower tank, said upper tank having inset in the under face metal strips provided with depending internally threaded nipples, said lower tank on the upper side having perforated metal strips inset therein and being 85 provided with threaded perforations, tubes having external threads at their opposite ends and engaged at one end in said nipples and at the other end in the strips in the lower tank, said lower threaded ends 90 being provided with lock nuts for abutting engagement with the strips in the lower tank. 95

2. In a radiator according to claim 1, a fin structure having slots into which the tubes fit.
3. A radiator comprising upper and lower tanks, circulating tubes connecting said tanks, and a removable fin structure having slots into which said tubes fit, said tanks

being provided with perforated ears and said fin structure being provided with Z bolts having threaded extremities passing ¹⁰ through said ears for the reception of retaining nuts.

CHARLES LEWIS LEHMAN.
JOHN GEORGE CONNELL.
